UNITED STATES PATENT OFFICE

MICHAEL VACCARO, OF PORT CHESTER, NEW YORK

STORAGE BATTERY TERMINAL CONNECTER

Application filed August 21, 1929. Serial No. 387,502.

This invention relates to an improved connector or clamp for use in association with the post on a conventional storage battery.

In carrying the invention into effect, I have evolved and produced what I believe to be a new and novel type of clamp which is secure, dependable, efficient, and adjustable for effectively maintaining a conductor wire safely and properly on the battery post.

The particular details will become more readily apparent from the following description and drawings:

In the drawings:

15 Figure 1 is a fragmentary top plan view of a portion of a battery with the improved connector associated with the post.

Fig. 2 is an end view of one of the parts of the connector.

20 Fig. 3 is a cross section on the line 3—3 of Fig. 1.

Fig. 4 is a view of one of the details.

Fig. 5 is a detail section on the line 5—5 of Fig. 1.

25 In Fig. 1, the reference character 6 designates an ordinary storage battery and 7 the usual tapered post. The connector comprises two parts, one of which includes a ring 8 which embraces the post and carries 30 a screw threaded stud 9 to accommodate a retaining nut 10. The other part comprises a longitudinally bowed binding member which is of channel-shaped cross section as generally indicated by the reference character 11. This is of a proportion to cause 35 the top and bottom flanges 12 to straddle the ring 9 and to bear against the post 7.

The inner edges 13 are of curvate configuration to bear firmly against the post. 40 The web portion of the channel is formed with an aperture 14 to permit passage of the screw threaded stud 9. Formed integral with the part 11 is a socket 15 in which the conductor wire 16 is mounted.

45 With this arrangement, it is obvious that by tightening the nut 10 on the stud 9, the channel-shaped part 11 will be bound firmly against the post 7 whereby to simultaneously secure both parts of the clamp to the 50 post. The simplicity of the invention is

such as to make it unnecessary to enter into a more detailed description. In fact, it is thought that the features and advantages of the construction will be quite evident after considering the description in connection with the drawings. Consequently a more specific description is regarded as unnecessary.

Minor changes in shape, size, and rearrangement of details, coming within the field of invention claimed may be resorted to in actual practice if desired.

Having thus described my invention, what I claim as new is:

1. As a new product of manufacture, a connector including a longitudinally bowed channel-shaped member having its flanges formed with curvate edge portions co-operable with a battery post, and a socket at one end of said channel-shaped member adapted for anchorage of a conductor.

2. As a new product of manufacture, a connector including a longitudinally bowed channel-shaped member having its flanges formed with curvate and portions co-operating with the battery post, and a socket at one end of said channel shaped member adapted for anchorage of a conductor, a ring shaped battery post embracing member, having a threaded stud, the web of said channel member being apertured to permit of such being projected therethrough and beyond said rim, a clamp not cooperating with said threaded nut to effect the drawing together of the battery post and said curvate edge portions of the channel member in relatively immovable relationship.

In testimony whereof I affix my signature.

MICHAEL VACCARO.
